Hanselby, Jr.
Attorney

UNITED STATES PATENT OFFICE.

CHARLES W. RAND, OF ABERDEEN, SOUTH DAKOTA.

SIDE-WALL REGISTER.

Application filed November 17, 1920. Serial No. 424,734.

To all whom it may concern:

Be it known that I, CHARLES W. RAND, a citizen of the United States, residing at Aberdeen, in the county of Brown and State 5 of South Dakota, have invented certain new and useful Improvements in a Side-Wall Register; and I do hereby declare the following to be a full, clear, and exact description of the invention, such as will 10 enable others skilled in the art to which it appertains to make and use the same.

The object of the invention is to provide a side wall or laterally open heating and ventilating register for use in connection 15 with one pipe furnaces or heating plants, primarily to avoid the disadvantages incident to a floor register, ordinarily required in connection with a furnace of this type and which interferes with the arrangement 20 of carpets and rugs on the floor, furnishes a means of ingress of dust and dirt in cleaning and sweeping the floor and constitutes a menace, particularly to small children, in traversing the floor; in the second place 25 to afford a means whereby the heating and ventilating operation of the plant may be applied simultaneously and equally to a plurality of rooms or apartments separated by an intervening partition wall with a view 30 to securing a more uniform heating and ventilating of the interior of a compartmental structure; and furthermore to afford means whereby heat may be communicated to upper floors of a building in addition to 35 being distributed to the lower floor thereof as with the ordinary construction and arrangement of a single pipe furnace; and with these objects in view the invention consists in a construction and combination 40 of parts of which a preferred embodiment is shown in the accompanying drawings, wherein:

Figure 1 is a sectional view of a portion 45 of a building equipped with a double distributing or partition wall register of a type embodying the invention in connection with a conventional form of single pipe heating unit and having associated therewith means for communicating heat to an upper floor 50 of the same building.

Figure 2 is a perspective view of a register embodying the invention indicating its relation with the heating plant.

Figure 3 is a horizontal sectional view of 55 the register on the plane indicated by line 3-3 of Figure 1.

Figure 4 is a vertical sectional view of the same on the plane indicated by the line 4-4 of Figure 3.

Figure 5 is a detail section on the plane 60 indicated by line 5-5 of Figure 3.

Figure 6 is a detail view of one of the removable guards covering the outlet of the register.

The register which for convenience of 65 illustration, is shown in connection with a conventional form of single pipe furnace having the heating unit 10 enclosed in the concentric inner and outer hot air and cold air drums 11 and 12 consists of a casing 13 which is shown as of rectangular form, and is adapted to be incorporated in or let into a partition wall 14 of a building separating two rooms or apartments thereof and spanned longitudinally by a bearing plate 70 15 of a width substantially corresponding with the thickness of the partition wall, said casing being divided interiorly to form a central hot air passage 16 and a surrounding cold air passage 17, each of which is open at opposite sides of the casing as shown 75 respectively at 18 and 19, a collar 20 which bounds the hot air passage being suspended in the casing and being adapted to fit the upper end of the hot air drum of the furnace as indicated in Figure 1.

Preferably as indicated in the drawing, the hot air outlet openings 18 are disposed above the cold air inlet openings 19, not only for convenience in the construction of the 80 register, but in order that the column of hot air may be afforded a head and may be readily displace the cold air which naturally 85 seeks the floor level of the room or apartment and is intended to be received by the cold air passage 17, to the end that a more uniform and active circulation of air in the 90 room may be effected.

Depending from the bearing plate 15 there 95 is preferably arranged a deflector or division plate 21 serving to more effectually divide the column of hot air rising through the hot air passage and cause it to be distributed with equality to the lateral outlets which are in communication respectively with the rooms or apartments upon opposite sides of the plane of the intervening partition wall 14. Moreover in order to provide for the direct communication of heated air to upper 100 floors of the building, the bearing plate 15 105 may be provided with openings 22 with

which as indicated in Figure 1 may be connected stacks 23 leading to registers 24, or equivalent means of distribution.

Obviously when the direct communication of heated air to an upper floor is not required the openings in the bearing plates may be suitably covered or closed by removable caps 15 shown in Figure 5. Also it will be understood that any suitable conventional means for rendering the walls of the casing relatively heat non-conducting may be provided as a means of safety or security against the overheating of adjacent inflammable objects such as the flooring or other wood work of the building, as, for example, an asbestos interlining 30, arranged between lamina 31, particularly in the end walls of the casing as indicated in Figures 3 and 5.

20 Removably fitted upon the side portions of the casing at opposite sides of the plane of the partition wall are guards 25, one of which is shown detached in Figure 6, the same having side plates 26 and a wire screen 25 or equivalent filler 27 serving to present a neat and ornamental appearance in the room or apartment and at the same time prevent objects from falling into the passages in communication with the drums of the heating units.

Moreover, in the preferred construction an air space 32 is provided between the end walls of the casing and the adjacent walls of the hot air passage, so that in practice the latter is completely surrounded by a protection air space, serving to guard adjacent wood work and in carrying out my principle

of protection the bearing or bridge plate 15, may consist, as shown, of separated upper and lower elements 15^b and 15^c to form an 40 intervening air space 15^d (see Figures 4 and 5) with the upper element laminated and having an asbestos interlining 15^e.

Having thus described the invention, what I claim is:—

45 1. A wall register having a casing, an attaching collar in said casing providing a warm air passageway and spaced from the outer wall thereof to provide a cold air passageway, said collar at its upper extremity flaring outwardly to divide said passageways, a plate above and disposed over said collar, a deflector depending from said plate, and means open on opposite sides of the passageway for the upward passage of heated air through said plate.

50 2. A wall register having a casing, an attaching collar in said casing providing a warm air passageway and spaced from the outer wall thereof to provide a cold air 60 passageway, said collar at its upper extremity flaring outwardly to divide said passageway, a plate above and disposed over said collar, a deflector depending from said plate, means providing air spaces adjacent 65 the upper end of said casing, and said plate being constructed with an air passageway in communication with said air spaces.

In testimony whereof I affix my signature in presence of two witnesses.

CHARLES W. RAND.
